COMBINED RADIO FRONT PANEL AND ESCUCHEON

Melvin H. Boldt, Glenview, Ill., assignor to Zenith Radio
Corporation, a corporation of Delaware

Application April 10, 1959, Serial No. 55,438

Term of patent 7 years

(Cl. D56—4)

Figure 1 is a front elevational view of a combined radio front panel and escutcheon showing my new design; Figure 2 is a side elevational view thereof; and

Figure 3 is a top plan view, partially in section, showing the formation of the grille of my design.

The dominant features of my design reside in those portions of the drawing shown by means of full lines.

I claim:

The ornamental design for a combined radio front panel and escutcheon, substantially as shown and described.
